THERMAL SWITCH

Original Filed Feb. 10. 1922 2 Sheets-Sheet 2

Patented Jan. 25, 1927.

UNITED STATES PATENT OFFICE.

HUBERT CHILDRESS HAWKINS, OF WINSTON-SALEM, NORTH CAROLINA.

THERMAL SWITCH.

Application filed February 10, 1922, Serial No. 535,567. Renewed November 13, 1926.

This invention aims to provide a simple but effective means whereby a signal may be sounded, responsive to a rise of temperature, the device being of peculiar utility for signalling when a fire starts in a building.

The preferred embodiment of the invention is shown, but a mechanic may make changes therein, within the scope of what is claimed, without departing from the spirit of the invention or avoiding the charge of infringement.

In the drawing:—Figure 1 shows in perspective, a device constructed in accordance with the invention, mounted in the ceiling of an apartment; Figure 2 is an elevation wherein parts are broken away, and sectioned; Figure 3 is a vertical section on the line 3—3 of Figure 2; Figure 4 is a bottom plan; Figure 5 is a section on the line 5—5 of Figure 2; Figure 6 is a diagram showing the circuits which may be used.

The numeral 1 denotes an apartment comprising a ceiling 2, a floor 3 thereabove, and joists 4 between the ceiling and the floor. A register 5 is attached by securing elements 6 to the ceiling 2 and includes a tubular neck 7 projecting through the ceiling.

A back plate 8 is provided, and a casing 9 is mounted on the back plate, the parts 8 and 9 constituting a support, the back plate being held on one of the joists 4 by securing devices 10. The casing 9 has side flanges 11 through which pass securing members 12 engaging the back plate 8, the casing 9 thus being held on the back plate. The casing 9 is open at its bottom, as shown at 14, and includes a top 15. A partition 16 extends across the casing 9 and is spaced from the top 15 to form a compartment 17. Spaced tubes 18 are located in the casing 9 and are closed at their lower ends, the upper ends of the tubes being connected to the partition 16, the partition having openings 19 which establish communication between the tubes and the compartment 17. The tubes 18 and the compartment 17 form an air chamber.

The device includes a conduit, denoted generally by the numeral 20 and including an inverted U-shaped part 21, which may be made of metal, a hand valve 22 being interposed in the part or pipe 21. One end of the pipe 21 is connected to the top 15 of the casing 9 and communicates with the compartment 17. The other end of the pipe

21 extends downwardly and is connected by a coupling 24 to a tube 23, the tube preferably being made of glass or some other material which is neither an electrical conductor nor subject to attack by mercury or acid. A clip 25 is disposed beneath the coupling 24 and holds the tube 23 on the back plate 8. The numeral 26 marks a U-shaped pipe which may be made of metal, one end of the said pipe being connected by a coupling 27 to the tube 23, the other end of the pipe 26 being connected by a coupling 28 to a tube 29, which may be made of glass, the upper end of the tube 29 being closed by a cap 30. Clips 31, located adjacent to the cap 30 and the coupling 28, hold the tube 29 on the back plate 8. The parts 23, 26 and 29 may be described as a U-shaped portion of the conduit which is denoted generally by the numeral 20. A conducting liquid 48, which may be mercury or any other suitable substance, stands in the parts 26, 23 and 29 of the conduit. Terminals 32 are mounted in the tube 23 and cooperate with the conducting liquid 48, the terminals being spaced vertically. Conductors 33 lead from the terminals 32 to binding posts 34 on the back plate 8. Vertically spaced terminals 35 are mounted in the tube 29 and cooperate with the conducting liquid 48, the terminals 35 being connected by conductors 36 with binding posts 37 on the back plate 8. The metallic pipe 26 of the conduit 20 carries a binding post 38.

A conductor 39 is connected to the binding post 38, a battery 40, or other source of electrical energy, being interposed in the conductor 39. The numeral 41 marks a conductor, one end of which is connected to the conductor 39, the other end of the conductor 41 being adapted to be mounted in any of the binding posts 34. A relay 42 is interposed in the conductor 41 and is adapted to close an open circuit 43, including a source 44 of electrical energy. A signal 45 is interposed in the circuit 43. One end of a conductor 46 is connected to the conductor 39, the other end of the conductor 46 being adapted to be mounted in any of the binding posts 37. A signal 48, such as a drop annunciator, is interposed in the conductor 46. If desired, the signal 47 may be placed in the lobby of a hotel, the register 5, the casing 9 and attendant parts being located in a guest room, and the sig-

nal 45 being placed in a hose house, the office of a fire marshal, or in some other similar place.

Under ordinary temperatures, the conducting liquid 48 is in contact with the terminals 32 and the metallic part 26 of the conduit 20. Then there is established a closed circuit comprising the liquid 48 the pipe 26, the binding post 38, the conductor 29, the conductor 41, one of the binding posts 34, the corresponding conductor 33, the adjacent terminal 32, and the liquid 48. Likewise under ordinary temperatures, the conducting liquid 48 is not in contact with any of the terminals 35, the device including, therefore, an open circuit including the liquid 48, the pipe 26, the binding post 38, the conductor 39, the conductor 46, one of the binding posts 37, the corresponding conductor 36, and the adjacent terminal 35.

When fire occurs, the air in the tubes 18 and the compartment 17 expand, pressure being transmitted to the conduit 20, the conducting liquid 48 being forced downwardly in the tube 23 and upwardly in the tube 29, the liquid moving out of contact with the terminal 32 wherewith the conductor 41 is connected, the liquid moving into contact with the terminal 35 wherunto the conductor 46 is connected. The result is that the circuit of which the conductor 41 is a part is opened, the circuit of which the conductor 46 is a part being closed. When the circuit of which the conductor 41 is a part is opened, the relay 42 closes the signal circuit 43, and the signal 35 is sounded. When the signal of which the conductor 46 is a part is closed, the signal 47 is operated. Thus, both the clerk in a hotel, and a fire marshal or engine house attendant may be admonished that a fire has started in the apartment 1.

The valve 22 may be closed in order to prevent the conducting liquid 48 from running back into the compartment 16 and the tubes 18, during the shipment, installation or repairing of the device. Since the con-

ductor 41 may be connected with any of the vertically spaced terminals 32, through the instrumentality of the binding posts 34 and 59 the conductors 33, and in view of the fact that the conductor 46 may be connected to any of the vertically spaced terminals 35 by way of the binding posts 37 and the conductors 36, the signals 45 and 47 may be 55 made to operate at different temperatures existing in the apartment 1. Since a plurality of the tubes 18 are provided, and because these tubes are spaced apart, a maximum area is presented to the superheated 69 air in the apartment 1, and the device is caused to be quickly and delicately responsive to temperature changes.

What is claimed is:—

1. In a device of the class described, a 65 casing open at one end and provided at its other end with a compartment; a plurality of tubes in the casing, the tubes communicating at one end with the compartment, each tube being closed at its other end, 70 the tubes being spaced apart transversely; a conduit communicating with the compartment; a conducting liquid in the conduit; and a terminal in the conduit and cooperating with the liquid, the open end of the 75 casing serving to admit heated air to the tubes, the casing serving to retain the air about the tubes, the plurality of tubes and the compartment presenting a large area to the heated air thereby to cause the conducting liquid to move rapidly and sensitively 80 with respect to the terminal.

2. The combination with the wall of a room, of a casing mounted in the wall and open at one end to communicate with the 85 room, the casing being provided with internal means for confining air, a conduit communicating with said means, a conducting liquid in the conduit, and a terminal in the conduit and cooperating with the liquid. 90

In testimony that I claim the foregoing as my own, I have hereto affixed my signature.

HUBERT CHILDRESS HAWKINS.
